UNITED STATES PATENT OFFICE.

HERMAN STEECK, OF WINONA, MINNESOTA.

WAGON END-GATE.

SPECIFICATION forming part of Letters Patent No. 536,161, dated March 19, 1895.

Application filed July 21, 1894. Serial No. 518,213. (No model.)

To all whom it may concern:

Be it known that I, HERMAN STEECK, a citizen of the United States, residing at Winona, in the county of Winona and State of Minnesota, have invented certain new and useful Improvements in End-Gates; and I do declare the following to be a full, clear, and exact description of the invention, such as will enable others skilled in the art to which it appertains to make and use the same, reference being had to the accompanying drawings, and to the letters of reference marked thereon, which form a part of this specification.

The invention relates to end gates for wagons.

It has for its object to provide means for receiving and holding the end gate and releasing the same from the body of the wagon.

With these objects in view the invention consists in certain features of construction and combination of parts which will be hereinafter fully described and claimed.

In the accompanying drawings of which like letters of reference denote corresponding parts,—Figure 1, is a perspective view of a portion of a wagon body showing my invention applied. Fig. 2, is a detail view of the guide plate, and Fig. 3, is a similar view of the locking latch.

In the drawings A denotes the side board of a wagon body and B the end gate. The guide plate C is composed of two laterally projecting wings c which are secured to the side board, two inwardly projecting flanges c' and a base flange c'' to receive and support the end gate, and a screw threaded extension c''' which passes through the floor and secures the side boards thereto by means of a nut c''. Secured to the tail gate within convenient

reach is a latch D consisting of a base plate 40 d having outwardly projecting ears d' between which is pivoted a lever d² having at one end an inwardly projecting lug d³ which is adapted to enter a hole d⁵ in one of the flanges of the guide plate and be held therein 45 by the spring d⁴ secured with one end to the plate d and with its other end bearing against the operating end of the lever d².

In operation, when it is desired to remove the gate from the wagon the free ends of the 50 levers d² (it being understood that my invention is applied to the opposite sides of the body) are depressed thereby withdrawing the lug d³ from the holes d⁵ of the flange and allowing the gate to be lifted from the guide 55 plate.

Having thus described my invention, what I claim, and desire to secure by Letters Patent of the United States, is—

The combination with the wagon body, 60 guide plates each composed of two laterally projecting wings secured to the side boards, inwardly projecting flanges having a base flange from which projects a downward screw threaded rod, one of said flanges being provided with a hole, end gate, latches secured to each end thereof, each latch composed of a base plate having ears, a lever pivoted between said ears and provided with a lug which is adapted to enter the hole in the flange and 65 a spring for holding the lug in said hole, substantially as herein described.

In testimony whereof I affix my signature in presence of two witnesses.

HERMAN STEECK.
